Attorney

UNITED STATES PATENT OFFICE.

WILLIAM H. HOLLMANN, OF LORETTA, TENNESSEE.

CULTIVATOR.

1,353,342.

Specification of Letters Patent. Patented Sept. 21, 1920.

Application filed April 19, 1920. Serial No. 375,068.

To all whom it may concern:

Be it known that I, WILLIAM H. HOLLMANN, a citizen of the United States, residing at Loretto, in the county of Lawrence 5 and State of Tennessee, have invented certain new and useful Improvements in Cultivators, of which the following is a specification, reference being had to the accompanying drawings.

10 This invention relates to certain improvements in cultivators and has relation more particularly to a device of this general character comprising a plurality of ground working members assembled in gang and capable of relative adjustment, and it is an 15 object of the invention to provide novel and improved means for maintaining said members substantially fixed in a desired adjusted position and which means also serves as a 20 fender to prevent cutting or other injury to the plants when the cultivator is in use.

Another object of the invention is to provide a novel and improved arm or lever adapted to be applied in a manner to maintain 25 the ground working elements in substantially a fixed position and which member also serves as a guard or fender to prevent the cultivator, during a working operation, from injuring the plants.

30 The invention consists in the details of construction and in the combination and arrangement of the several parts of my improved cultivator whereby certain important advantages are attained and the device rendered simpler, less expensive and otherwise 35 more convenient and advantageous for use, as will be hereinafter more fully set forth.

The novel features of my invention will hereinafter be definitely claimed.

40 In order that my invention may be the better understood, I will now proceed to describe the same with reference to the accompanying drawings, wherein:

Figure 1 is a view in top plan illustrating 45 a cultivator constructed in accordance with an embodiment of my invention; and

Fig. 2 is a transverse vertical sectional view taken through the device as illustrated in Fig. 1.

50 As disclosed in the accompanying drawings, B denotes a beam of a conventional type and with which coact in a well known manner the handle members H.

Vertically disposed through the rear portion 55 of the beam B are the bolts 1 and 2 spaced apart longitudinally of the beam B

and which bolts are also directed through the cross members 3 and 4 respectively whereby said members are capable of swinging movement. The head of each of the 60 bolts 1 and 2 is preferably downwardly disposed so that the clamping nut 5, or the like, may be suitably engaged with said bolt at a point above the beam B although this particular arrangement is not essential. 65

The members 3 and 4 extend beyond the opposite side of the beam B and are arranged in parallelism and the members 4 are two in number and superimposed one upon the other. The members 4, at their 70 end portions and at predetermined points intermediate said end portions, are connected by the bolt 6, or the like, which serves to maintain the members 4 in assembled relation or against movement one independently 75 of the other.

7 denotes a brace strap, preferably of metal, and having its opposite end portions held to the upper member 4 by the end bolts 6. The strap or member 7 is arched so that 80 the same may extend over the beam B and rest upon the upper face of said beam and the central portion of the member or strap 7 is engaged by the bolt 2. By this means, the members 4 are effectively reinforced so 85 as to withstand strain imposed thereupon when my cultivator is in use.

Carried by and preferably disposed through the member 3 are the members or bolts 8 spaced apart longitudinally of said member 90 3 and each of said bolts or members 8 serves as a pivot for the forward end portion of the rearwardly directed shank 9 of a ground engaging member and which members may be spring teeth or as otherwise preferred. 95

The shanks 9 extend between the members 4 and in the complete assembly, the bolts or members 6 are arranged at opposite sides of each of the shanks 9. 10 denotes a reinforcing strap or member, also preferably of 100 metal, coacting with the member 3 and having its opposite end portions anchored to said member by the end bolts 8. The member 10 is also arched to extend over and bridge the upper face of the beam B and 105 the central portion has also disposed therethrough the bolt 1 whereby an additional point of attachment for the strap or member 10 is provided.

11 denotes a set lever or arm, preferably 110 of metal, and which is provided at one end portion with a foot or extension 12 adapted

to engage a side face of the beam B and clamped thereto through the instrumentality of the bolt 14 extending both through the beam B and said foot or extension 12. 5 The arm or lever 11, at a point inwardly of but in close proximity to the foot or extension 12 is skewed or twisted, as at 15, whereby the side or flat faces of the arm or lever 11 throughout the major portion thereof are 10 substantially at right angles to the side or flat faces of the extension or foot 12 so that said lever or arm 11 may be properly engaged with the adjacent end bolts 6 and 8. With the arm or lever 11 in applied position, the cross members 3 and 4 are held in 15 substantially a fixed position or against swinging movement and in order that the member or lever 11 may maintain the members 3 and 4 in different desired adjustments 20 about the bolts 1 and 2, I provide the rear portion of the arm or lever 11 with the longitudinally spaced openings 16, herein disclosed as five in number and so arranged to permit the maintenance of the members 3 25 and 4 in three different positions. In order to facilitate the proper functioning of the arm or lever 11, the portion thereof immediately adjacent the twist or screw 15 is arcuate while the free or rear portion of said 30 arm or lever 8 is substantially straight.

The portion *a* of the arm or lever 11 rearwardly of the twist or screw 15 is of such width as to have its outer longitudinal edge or margin extend beyond the adjacent ends 35 of the members 3 and 4 irrespective of their adjustment. By this means, the arm or lever 11 serves as a fender and prevents the adjacent ends of the members 3 and 4 coming into contact with the plants during a 40 working operation and which contact would result in the breaking or other injury of the plants. However, my improved arm or lever, on account of its particular construction and manner of application, during a 45 working operation, will come in contact with a plant and throw or bend the same to one side without injury thereto and which function I have found of particular advantage in the cultivation of cotton although it 50 is to be understood that this material benefit would be present should the plants be of a different character or species. It is to be understood that the arm or lever 11 constitutes the specific feature of my present

invention, and for which reason I wish to 55 be understood that I do not limit myself to the use of this arm or lever 11 in connection with a cultivator of the type hereinbefore described and as illustrated in the drawings,

It is also to be particularly noted that 60 the arcuate portion of the arm or lever 11 extends in advance of the forward cross member 3 and inwardly thereof so that the requisite action of the arm or lever as a fender is materially facilitated. 65

From the foregoing description, it is thought to be obvious that a cultivator constructed in accordance with my invention is particularly well adapted for use by reason of the convenience and facility with 70 which it may be assembled and operated, and it will also be obvious that my invention is susceptible of some change and modification without departing from the principles and spirit thereof, and for this reason I do 75 not wish to be understood as limiting myself to the precise arrangement and formation of the several parts herein shown in carrying out my invention in practice except 80 as hereinafter claimed.

I claim:—

A cultivator comprising, in combination, a beam, a pair of cross members carried by the beam at spaced points longitudinally thereof, said cross members being pivotally 85 connected with the beam, ground working members embodying forwardly extending shanks having the forward ends thereof secured to the foremost of said cross members, and the rearmost of said cross members embodying spaced members adapted to receive the shanks of said ground working members therebetween, spacing or clamping bolts extending through said last named spaced members intermediate said shanks 90 and spaced therefrom, whereby said shanks are shiftable transversely within said last named cross members, an arm connecting the adjacent ends of the cross members and secured to the beam at a point in advance 95 thereof, the outer margin of the arm extending beyond the outer ends of the cross members whereby said arm constitutes a fender. 100

In testimony whereof I hereunto affix my 105 signature.

WILLIAM H. HOLLMANN.
